SEAL

Filed Oct. 31. 1927

Inventor:

Harold V. Atwell,
Brydgesforth, Lee, Chittenden, Vt.
Attest,

UNITED STATES PATENT OFFICE

HAROLD V. ATWELL, OF HAMMOND, INDIANA, ASSIGNOR TO STANDARD OIL COMPANY,
OF WHITING, INDIANA, A CORPORATION OF INDIANA

SEAL

Application filed October 31, 1927. Serial No. 229,990.

The present invention relates to improvements in seals or vent valves, more particularly as applied to the vent pipes from the vapor space of gasoline storage tanks and 5 storage tanks for similar volatile liquids. It will be fully understood from the following description illustrated by the accompanying drawings, in which:

Figure 1 is a plan view of a valve or seal 10 construction embodying the present invention on the line 1 on Fig. 2, the cover being removed;

Fig. 2 is a sectional elevation on the line 2—2 of Fig. 1;

Fig. 3 is a cross-section on the line 3—3 15 of Fig. 2; and

Figs. 4 and 5 are details illustrating the mounting of the inverted cup.

The seal of the present invention is an improvement on the construction of the seal 20 shown in Patent No. 1,529,682, granted March 17, 1925, on the application of the present inventor and the Patent No. 1,553,848, granted September 15, 1925, on the application of 25 George W. Chencik.

Referring more particularly to the drawing, the numeral 5 indicates a vertical vent pipe section which communicates with a flanged pipe 6 adapted to be connected to a 30 vent pipe (not shown) from a storage tank. The vent pipe section 5 is preferably of rectangular cross-section and is surrounded by a pan 7 of rectangular horizontal section with suitable outwardly flaring sides 8. Over the 35 vent pipe 5 is provided an inverted rectangular cup 9, the sides of which surround and enclose the upper end of the vent pipe section 5. The inverted cup 9 carries a pivot rod 10 which preferably extends across it and projects 40 on either side to engage lugs 11 on the sides of the pan 7. The lugs 11 are cut away to receive the rod 10 as shown in Fig. 4. The inverted cup 9 is of sufficient depth so that its sides enter a body of sealing liquid maintained in the pan 7.

The inverted cup 9 is constructed upon the same principle as shown in the prior patents referred to above; that is, the center of gravity is offset with respect to the center of pressure. The portion of the inverted cup on the 50 left side of the pivot rod 10 (Figs. 1 and 2), is greater in area than the portion on the right side. The latter side is weighted as at 12 to bring the center of gravity into the vertical plane of the pivot rod 10.

With this construction, as is later apparent, when the sides of the inverted cup 9 are partially immersed in liquid in the pan 7, an excess of pressure within the vent pipe 5 will tend to cause one end of the cup 9 to rise, that end being the portion on the left of the pivot rod 10, as shown in Figs. 1 and 2. When the pressure within the vent pipe 5 is reduced below that of the exterior atmosphere, reverse action takes place, the side of the inverted 60 cup 9 having the larger area, being depressed.

As described in Patent No. 1,553,848, previously referred to, the ends 13 of the inverted cup 9 which are parallel to the pivot rod 10 may be cut away from their centers to each 65 side as shown at 14, to form openings of gradually decreasing area as said ends descend into the liquid in the pan 7. The sides may be similarly cut away as at 15. As a result of this construction, as the end of the pan is forced down into the liquid, a gradually decreasing aperture for the escape of vapors is provided, thereby tending to prevent sudden rushes of gases which would tend to rock the cup. In practice, it is found that this expedient is not so necessary on the end of the cup at which air is admitted and accordingly that end is shown unprovided with cut away 75 portions.

As a further means for preventing oscillation of the cup, weight means designated generally 16, are provided, preferably on each side of the cup. Each weight means 16 comprises a strap 17 adapted to lie on the surface of the cup and having depending por- 80 85 90

tions 18 which extend downwardly to the bottom of the pan 7. At their lower ends they are connected to a plate of substantial surface area. This plate may suitably be an angle-piece 19 of light metal. From each of the depending portions 18, straps 20 extend to the pivot rod 10 which passes through perforations therein so that when the cup 9 tilts, carrying with it one of the weight members 16, the latter acts as a rigid unit not subject to irregular movements which would tend to cause erratic movement of the cup.

The weight members 16 are of such mass that they prevent tilting of the seal until a certain excess pressure exists on one side or the other of the inverted cup. When this excess pressure is exerted the cup tilts lifting one of the weights 16 on its rising end. When the excess pressure is relieved the cup returns to its normal horizontal position. If it tends to go further it is relieved of the aforesaid weight member and the other side of the cup ascends, picking up the other weight 16 which acts in opposition of the tilting movement. Not only does the weight of the members 16 tend to prevent oscillation, but the flat surfaces of the members 19 offer a substantial resistance to movement through the sealing liquid. As before pointed out the members 19 are capable of moving in a single path so that the resistance is uniform and without irregularities.

As previously indicated, most of the rocking to which the inverted cup is subject appears to occur when vapors are being vented. Accordingly only the weight means on the larger side of the cup, that is the side on the left in Figs. 1 and 2, may be provided with a damper plate. Since, however, the weight means on both sides act to prevent or minimize rocking however induced, it is preferred to provide weight means on both sides of the cup.

A suitable protecting cover 21 is provided over the pan 7, being supported thereon by lugs 22.

Although the present invention has been described in connection with the details of a specific embodiment thereof, it is not intended that such details shall be regarded as limitations upon the scope of the invention except in so far as included in the accompanying claims.

I claim:

1. A seal comprising an inverted cup adapted to tilt to one side or the other in accordance with the difference of pressure above and below said cup, means adapted to maintain sealing liquid around said cup, conduit means communicating with the underside of said cup, weight means adapted to be lifted by an end of said cup when it rises, and a resistance plate adapted to be located in said liquid and constrained to

move by said weight means in a uniform path therethrough.

2. A seal comprising an open conduit member communicating with a vapor space, a pan surrounding said conduit member and adapted to contain a liquid, an inverted pivoted cup over said conduit member and having its sides partially immersed in liquid in the pan, said cup having its center of pressure offset from its center of gravity, a weight member on one side of said cup adapted to be raised by said side when it rises, said weight member being provided with a resistance plate adapted to be immersed in said liquid and constrained to move therethrough with the weight in a definite regular path.

3. A seal comprising an open conduit member communicating with a vapor space, a pan surrounding said conduit member and adapted to contain a liquid, an inverted pivoted cup over said conduit member and having its sides partially immersed in the liquid in the pan, said cup having its center of pressure offset from its center of gravity, a weight member on one side of said cup adapted to be raised by said side when it rises, said weight member being constituted by a rigid structure pivotally mounted and comprising a resistance plate adapted to be immersed in the liquid.

4. A seal comprising an inverted cup adapted to tilt to one side or the other in accordance with the difference of pressure above and below said cup, means adapted to maintain sealing liquid around said cup, conduit means communicating with the underside of said cup, a pair of weight means, one of which is adapted to be lifted by one end of the cup when it rises and the other is adapted to be raised by the other end of the cup when it rises, and a pair of resistance plates adapted to be located in said liquid and constrained to move in uniform paths therethrough.

5. A seal comprising an open conduit member communicating with a vapor space, a pan surrounding said conduit member and adapted to contain a liquid, an inverted pivoted cup over said conduit member and having its sides partially immersed in liquid in the pan, said cup having its center of pressure offset from its center of gravity, a pair of weight members, one on each side of said cup and adapted to be raised by the corresponding side of the cup when it rises, each of said weight members being provided with a resistance plate adapted to be immersed in said liquid and constrained to move therethrough with the weight in a definite regular path.

6. A seal comprising an open conduit member communicating with a vapor space, a pan surrounding said conduit member and adapted to contain a liquid, an inverted

pivoted cup over said conduit member and having its sides partially immersed in the liquid in the pan, said cup having its center of pressure offset from its center of gravity, 5 a pair of weight members, one on each side of said cup and adapted to be raised by the corresponding side of the cup when it rises, each of said weight members being constituted by a rigid structure pivotally mounted 10 and comprising a resistance plate adapted to be immersed in the liquid.

In testimony whereof I have hereunto set my hand this 15th day of October, 1927.

HAROLD V. ATWELL.
